[57] ABSTRACT

Synthetic organic fibers are dyed to a dark brown to

black shade with a mixture of dyes, one of the dyes in the mixture being a green to blue dye having an absorption spectrum in which the peak value of absorbance is between 600 and 700 nanometers, said green to blue dye being further characterized in that the ratio of absorbance at 700 nanometers to the absorbance at the peak value between 600 and 700 nanometers is at least 0.05. The presence of this green to blue dye reduces or eliminates transmittance of red light along the fiber axis, so that no reddish glow is seen when the ends of the fibers are observed. The dark brown to black fibers are thus well suited for use in artificial furs.
